CRANE WITH PORTABLE BOOM

Berton M. Mathias, Monte Vista, Colo.

Application March 22, 1949, Serial No. 82,898

4 Claims. (Cl. 212—144)

1

This invention relates to power cranes and similar devices, and more particularly to a power crane having a foldable boom which can be reduced in length for convenience in transportation of the crane, and can be quickly and easily extended for use.

It is among the objects of the invention to provide an improved power crane having a foldable boom which can be quickly and easily folded at one or more locations along its length to reduce the length of the boom for more convenient transportation of the crane from place-to-place, and which may also have a foldable tower or superstructure which may be quickly and easily lowered for transportation of the crane, so that the crane, during transportation, will be able to go around sharp curves, pass through underpasses and under overhead wires, will be more stable, particularly under adverse conditions, such as uneven road surfaces and high winds, and will occupy a much shorter space on a highway or in a railroad train, which has power-operated boom folding and unfolding means operative to fold the boom into as many as three super-imposed sections, and may also have power-operated means for raising and lowering the superstructure, and in which the foldable boom and boom folding and unfolding means are simple and durable in construction, economical to manufacture and install, and provides, when the boom is extended, a boom of equal strength to a non-foldable boom of the same general dimensions.

Other objects and advantages will become apparent from a consideration of the following description and the appended claims in conjunction with the accompanying drawings, wherein:

Figure 1 is a side elevation of a power crane having a foldable boom and foldable superstructure illustrative of the invention, with the boom in extended condition, and the superstructure raised;

Figure 2 is a view similar to Figure 1 with the boom folded and the superstructure lowered;

Figure 3 is a transverse cross-section on an enlarged scale on the line 3—3 of Figure 1;

Figure 4 is a longitudinal cross-section of a fragmentary portion of the boom and boom-folding means on the line 4—4 of Figure 3;

Figure 5 is a rear elevation of the crane illustrated in Figure 1 with the crane superstructure in raised position;

Figure 6 is a longitudinal cross-section of a fragmentary portion of the crane illustrated in Figure 5, and is taken substantially on the line 6—6 of Figure 5; and

2

Figure 7 is a transverse cross-section on an enlarged scale of a fragmentary portion of the boom, taken on the line 7—7 of Figure 1.

With continued reference to the drawings, the crane has a body 10 which may be of conventional construction, housing a power plant 11, and cable drums 12 and 13 drivingly connected to the power plant and operated by the usual manual controls, not illustrated. The body 10 is pivotally mounted by means of a circular track 14 under its floor, upon a circular track 15 carried by a suitable frame supported on ground-engaging tracks 16 in the usual manner. Adjacent the controls, the body is provided, in its walls, with suitable windows 17, and has the usual space and other facilities for the operator of the crane. The elongated boom, generally indicated at 18, is pivotally connected at one end to the crane body 10 at the front edge of the bottom of the body by a suitable hinge connection 19, and carries, at its outer end, a pair of oppositely-disposed sheaves 20 over which pass the cable 21 which raise and lower the outer end of the boom. The cable 21 may be a continuous cable having its ends wound on respective cable drums in the crane body 10. From these drums the two parts of the cable pass upwardly and over respective sheaves 22 carried on the top of the superstructure, generally indicated at 23. From the sheaves 22 the cable portions pass respectively over the sheaves 20 at the outer end of the boom and then extend rearwardly toward the superstructure where they pass over respective sheaves 24 carried by respective clevises 25 extending forwardly from the superstructure-carried shaft 26 on which the sheaves 22 are mounted, and from the sheaves 24 the center portion of the cable extends forwardly and passes over a sheave 27 carried by a clevis 28 connected to a shaft 29 secured to the front end of the boom, which shaft also carries the sheaves 20 and a crown sheave 30 which is preferably located at the center of the width of the boom. A load cable 31 extends from a winding drum, not illustrated, over a sheave 32 secured to the crane body and thence over the crown pulley 30, around a suitable block, not illustrated, and has its end secured to the boom at a location adjacent the crown pulley, as indicated at 33.

In the arrangement illustrated, the boom 18 is provided in three separate sections including two end sections 34 and 35, and a center section 36. These boom sections are substantially square in cross-section, and the center section 36 comprises four longitudinally-extending angle irons 37 connected together by web bracing 38 extend-

ing along the four sides of the boom section. The center section 36 has, at each end, a square frame which may be conveniently formed of lengths of angle iron welded together and welded to the corresponding ends of the longitudinal angle irons 37. These end frames are indicated at 39 and 43, and the frame 39 has, on its lower side, outwardly-extending apertured lugs 42, Figure 2, located respectively adjacent the opposite sides of the frame. A shaft 41 is transversely journaled on the section 36 near the frame 39, and at the upper side of the section, that is, the side of the section opposite the lugs.

A pair of gear sectors 43 is secured to the end frame 40 of the boom center section 36 at the 15 end of the section adjacent the crane body 10 and these sector gears extend above the boom center section and outwardly from the center section of the boom to overlie the adjacent end portion of the boom end section 35 which is pivotally connected at its end opposite the center section 36 to the crane body 10.

The end section 35 of the boom also comprises four longitudinal angle irons 44 connected together by diagonal web braces 45 which extend along the four sides of the boom section. Beyond a location spaced from the center section 36, the upper and lower angle irons 44 of the end section 35 of the boom converge toward each other and enter a box structure 46 at the end of the boom connected to the crane body. This box section 46 may be formed of suitable plates welded together, and carries the lugs by means of which the corresponding end of the boom end section 35 is pivotally connected to the bottom, front end of the crane body. As this pivotal connection may be entirely conventional, it has not been illustrated, in detail.

The outer-end section 34 of the boom also comprises four longitudinal angle irons 47 which are interconnected by diagonal web bracing 48 extending along the four sides of the section and converge toward their outer ends to a box structure 49 in which are mounted suitable bearings for the sheave shaft 29. At its end adjacent the center section 36 of the boom, the end section 34 has a square end frame 50 from which extends apertured lugs 50', the apertures of which register with apertures in the lugs 42 on the lower side of the boom center section 36 to receive a pivot pin 51 which pivotally connects the boom outer-end section 34 and center section 36 at their adjoining ends and at the lower side of the boom.

Two semi-circular gear sectors 52 are secured to the end frame 50 of the boom outer section 34 at respectively opposite sides of the boom, and extend upwardly from the outer end section and outwardly from the end section 34 over the adjacent portion of the center section 36. The centers of these gear sectors are substantially concentric with the center of the pivot pin 51, and in addition to being connected to the end frame 50 of the boom section 34, they may be further reinforced by diagonal braces 53 extending from the outer corners of the gear sectors to the corresponding longitudinal angle irons of the boom end section.

Gears 54 are fixed on shaft 41 and mesh respectively with the sector gears 52 to rotate the sector gears about the axis of pivot pin 51.

When the boom 18 is in the extended condition, illustrated in Figure 1, and the shaft 41 is rotated in a clockwise direction, the gear sectors 52 will be rotated in a direction to fold the outer-end section 34 of the boom downwardly

5 and rearwardly until it overlies, and is superimposed upon the center section 36 of the boom.

A shaft 55 is transversely journaled in the outer-end frame 56 of the inner-boom section 35, and gears 57 fixed on this shaft mesh respectively with the gear sectors 43 secured to the adjacent end of the boom-center section 36. In addition to being secured to the end frame 40 of the boom-center section, the gear sectors 43 may be reinforced by diagonal braces 58 extending from the outer corners of the gear sectors respectively, to adjacent longitudinal angle irons 37 of the boom-center section.

The boom-center section 36 is provided, at its upper side, with outwardly-extending, apertured lugs 60 located at respectively opposite sides of the boom, and the end section 35 is provided with apertured lugs 61 which are disposed at the inner sides of respective lugs 60 with their apertures in alignment with the apertures of the lugs 60, and a shaft 62 extends through the lugs 60 and 61 and through the gear sectors 43 substantially concentric with the arcuate curvature of these gear sectors.

25 As is particularly illustrated in Figures 1 and 3, the shaft 55 is located at the lower side, and the shaft 62 is located at the upper side of the boom.

A chain sprocket 63 is fixed on the shaft 55, and a chain 64 extends around the sprocket 63 and around a sprocket 65 mounted on the shaft 66 by means of which the boom is pivotally connected to the crane body. The sprocket 65 is driven from the crane power plant by suitable means and under suitable manual control, not illustrated.

When the boom is in the extended position, illustrated in Figure 1, and the shaft 55 is rotated in a counter-clockwise direction, the gear sectors 43 will be rotated to fold the center section 36 of the boom upwardly and rearwardly to overlie the boom-end section 35.

A right-angle bearing bracket 67 is journaled on shaft 55 outside of the chain sprocket 63, and a similar right-angular bearing bracket 68 is journaled on shaft 62 outside of a chain sprocket 69 secured on shaft 62 at the outer side of one of the gear sectors 43. A beveled gear 70 is secured on shaft 55 outside of the bracket 67, and a beveled gear 71 is secured on shaft 62 outside of the bearing bracket 68. A connecting shaft 72 extends through the bearing brackets 67 and 68, and has, on its opposite ends, beveled gears 73 and 74 meshing respectively with the beveled gears 70 and 71, so that when the sprocket 63 is rotated by its power connection with the power plant of the crane, the sprocket 69 on shaft 62 will be simultaneously rotated, but in the opposite direction. A chain sprocket 75 is secured on shaft 41 at the outer end of the center section 36 of the boom, and a link chain 76 extends around the sprockets 69 and 75, so that the shaft 41 and the gears 54 will be driven whenever the shaft 55 is driven from the power plant of the crane.

With this arrangement, as the center section 36 of the boom is moved upwardly and rearwardly relative to the inner-end section 35, the outer-end section 34 will be simultaneously moved downwardly relative to the center section 36, so that when the sector gears 43 and 52 have been rotated through one-half of a revolution, the three sections of the boom will be superimposed, one upon the other, as illustrated in Figure 2.

After the three sections of the boom have been brought to the position illustrated in Figure 2, the outer-end section may be connected near its

outer end to the center section by suitable U-clamps 71, and the outer end of the folded boom may be supported by winding in the load cable 34 to support the folded boom in substantially horizontal position from the load cable sheave 32.

When the boom is unfolded or extended, the shafts 55, 62 and 41 are rotated in the opposite direction from the folding direction of these shafts, so that the center section 36 of the boom is moved upwardly and forwardly relative to the inner-end section 35, and the outer-end section 34 is moved forwardly relative to the center section 36. When the three boom sections have been brought to an aligned, end-to-end relationship, they are releasably secured in this position by suitable bolts 78 inserted through apertured lugs 79 carried by the center section 36 at respectively opposite ends thereof and overlying the adjacent ends of the end sections, the lugs overlying the outer-end section being at the upper side of the boom, and those overlying the inner-end section being at the lower side of the boom, as is particularly illustrated in Figure 1.

The superstructure 23 is generally pyramidal in shape, and is pivotally secured at its rear, lower edge to the rear, upper edge of the crane body 10 by apertured lugs 80 projecting outwardly in mutually aligned relationship from the superstructure and the crane body, and a shaft 81 extending through these lugs along the upper, rearward edge of the crank body. Semi-circular gear sectors 82 are secured to the superstructure and project rearwardly thereof with their centers of curvature substantially concentric with the shaft 81.

A shaft 83 is journaled in the crane body immediately below the sector gears 82 and carries gears 84 meshing respectively with the sector gears 82, and a chain sprocket 85. A drive shaft 86 is journaled in the crane body below the shaft 83 and carries a chain sprocket 87 and a link chain 88 extends around the sprockets 85 and 87 to drive the shaft 83 and gears 84.

When the superstructure is in its raised position, as illustrated in Figure 1, and shaft 83 is driven in a counter-clockwise direction, the sector gears 82 will be rotated to fold the superstructure rearwardly and downwardly from the raised position illustrated in Figure 1, to the lowered position illustrated in Figure 2, in which the rear side of the superstructure, when in raised position, is superimposed upon the rear end of the crane body 10.

The boom-supporting cable 21 may be removed entirely, or may be loosened and tightened as the boom is folded and unfolded, and the superstructure is lowered and raised, so as not to interfere with the folding and unfolding movements of the boom and the raising and lowering movements of the superstructure.

When the superstructure 23 is in raised position, it may be releasably locked in that position by suitable means, such as the apertured plates 90 extending from the upper portion of the crane housing to the lower housing of the superstructure near the forward end of the crane housing, and the rivets 91 and bolts 92 securing these plates to the crane housing and superstructure respectively.

The invention may be embodied in other specific forms without departing from the spirit or essential characteristics thereof. The present embodiment is, therefore, to be considered in all respects as illustrative and not restrictive, the scope of the invention being indicated by the

appended claims rather than by the foregoing description, and all changes which come within the meaning and range of equivalency of the claims are, therefore, intended to be embraced therein.

What is claimed is:

1. In a power-operated crane having a crane body, an elongated boom pivotally connected at one end to the crane body and including at least two lengthwise sections pivotally connected together at their adjoining ends, power-operated means carried by such sections at their adjoining ends to move said sections relative to each other between a folded position in which they are relatively superposed and an extended position in which they are in end-to-end relationship, and means carried by said boom sections at their adjoining ends for releasably locking said sections together in end-to-end relationship, said power-operated means comprising a pair of semi-circular gear sectors fixed on one of said sections, a transverse shaft journaled in the other of said sections, gears on said shaft respectively meshing with said gear sectors, and drive means extending from said shaft for drivingly connecting the latter to a crane power plant.
2. In a power operated crane having a crane body, an elongated foldable boom pivotally connected at one end to the crane body and including at least two lengthwise sections pivotally connected together at their adjoining ends, power operated means carried by said sections at their adjoining ends to move said sections relative to each other between a folded position in which they are relatively superimposed and an extended position in which they are in end to end relationship, and means carried by said boom sections at their adjoining ends for releasably locking said sections together in end to end relationship, said power operated means comprising gears mounted on said sections near their adjoining ends with the gears on one section meshing with the gears on the other section, and drive means connected to the gears on one of said sections for folding and unfolding said sections relative to each other.
3. In a power operated crane having a crane body, an elongated foldable boom including three sections the first of which is pivotally connected at one end to the crane body, the second of which is pivotally connected at one end to the other end of said first section at the upper side of the latter, and the third of which is pivotally connected at one end to the other end of said second section at the lower side of said third section so that when said boom is folded said second section will be superimposed on said first section and said third section will be superimposed on said second section, first boom folding means connected between said first and second sections, power operated means drivingly connected to said first boom folding means, second boom folding means connected between said second and third sections, and means drivingly connecting said first boom folding means to said second boom folding means.
4. In a power operated crane having a crane body, an elongated foldable boom including three sections the first of which is pivotally connected at one end to the crane body, the second of which is pivotally connected at one end to the other end of said first section and the third of which is pivotally connected at one end to the other end of said second section so that said sections will be relatively superimposed when said boom is folded,

first boom folding means connected between said first and second sections, power operated means drivingly connected to said first boom folding means, second boom folding means connected between said second and third sections, and means drivingly connecting said first boom folding means to said second boom folding means.
